DEVICE FOR SECURING MINIATURE RAILS TO MINIATURE RAILWAY BED UNITS

Stephen Schaffan, Irvington, N.J.

Application August 29, 1955, Serial No. 531,095

4 Claims. (Cl. 29—241)

This invention relates to miniature rail units such as are popularly used in miniature train systems and to the device for securing miniature rails to miniature railway bed units. Pursuant to the present invention, miniature rails may be rapidly and accurately secured to bed units automatically by novel means for positioning and holding the units in position in the assembly operation.

The parts may be assembled and moved out of the assembly position, by a novel apparatus, as will become apparent from a consideration of the drawings attached hereto, and from the following description. The drawings illustrate the application of the method and apparatus of this invention in several practical forms thereof.

In the drawings:

Fig. 1 is a fragmentary top plan view of a device which may be used to carry out the method of this invention, showing in full lines, retracted, a pair of bars to engage rails to be moved into engagement with C-shaped open holders on the miniature railway bed unit, and, showing, in dotted lines, said bars in their fully engaged position.

Fig. 2 is an enlarged plan view of the first plate member 26 and associated parts shown in Fig. 1, the second plate member 74 (which is shown in Fig. 1 as closed over the first plate member) being shown in Fig. 2 as open,

Fig. 3 is an enlarged, fragmentary, sectional view taken at line 3—3 of Fig. 2, showing one form of unit release lever which may be used in carrying out the invention, movably disposed in a recess in the plate,

Fig. 4 is an enlarged fragmentary view taken at line 4-4 of Fig. 1, showing the plate recess for receiving the slide bar finger.

Fig. 5 is an enlarged, fragmentary, transverse sectional view taken on line 5—5 of Fig. 2, showing the rail and rail holder receiving recesses provided in the plate,

Fig. 6 is a top plan view of the form of invention shown in Fig. 1, with the second plate which is movably mounted on the device, to be superposed over the miniature railway unit to hold the same in position during the assembly operation, shown elevated as it would be to facilitate removal of said unit after completion of the assembly operation.

Fig. 7 is a similar view, showing the second plate moved to its closed position over a unit positioned on the first plate, preparatory to moving the slide bars against the ends of the rails,

Fig. 8 is a similar view, showing the position of the slide bars at the completion of their operative stroke having moved the rails into the holders of the unit,

Fig. 9 is an enlarged, fragmentary, elevational view showing details of one form of means which may be used for connecting the second plate to the device, showing, in full lines, the position of the parts when the second plate is being moved to its open (dotted vertical) position, and their position when the second plate is held in closed (dotted horizontal) position.

2

Fig. 10 is an enlarged sectional elevational view taken on line 10—10 of Fig. 11,

Fig. 11 is a top plan view of a further form of device embodying the invention, prior to the positioning of a miniature railway bed unit therein,

Fig. 12 is a similar view showing miniature railway bed units positioned therein,

Fig. 13 is an enlarged fragmentary view of said form of the invention, showing the second plate closed over said miniature railway bed units.

Fig. 14 is an enlarged, sectional, elevational view, taken on line 14—14 of Fig. 11, and

Fig. 15 is an enlarged, fragmentary, sectional view, showing the manner in which a miniature rail unit is held in a C-shaped open holder of a miniature railway bed unit pursuant to the invention.

As shown in the drawings, this invention provides a novel method of securing miniature rails such as shown at 20 (Fig. 15) of T-shaped cross section within a plurality of registered spaced C-shaped open holders 21 formed on a miniature railway bed unit 22 (Fig. 12) or 23 (Fig. 6) said holders 21 extending above the plane 24 of a face 25 of said unit (Fig. 15),

Pursuant to the invention, the miniature railway bed unit is positioned on a registration plate 26 having rail-

receiving recesses 27 (Figs. 3 and 5) registered with the series of holders 21 when the unit 22 is positioned on plate 26. The recesses 27 (Figs. 2 and 8) correspond with the axial lines of the plurality of holders 21 (as will be readily apparent from Fig. 2 from which it will be noted that the recesses 27 are in line with the axial lines of grooves 45 to receive said holders 21). The plate 26 is preferably provided with registration means, such as stop pins 28, 29 (Figs. 1, 2, 7 and 8) which serve to both position the unit 22 in correct registry on the plate 26 and also to stop the slide bars 30, 31 from excessive movement in operation, as presently explained. The invention may be used for units 22 of a plurality, as indicated in Fig. 12.

of relatively straight form such as shown in Fig. 12, 40 or of other form such as the arcuate form shown at 23 in Fig. 6, the said units having a plurality of cross ties 32 connected, as at 33, for spaced, transverse disposition (Fig. 6). A plurality of spaced C-shaped open 45 holders 21 are formed along one of the sides of the units 22, 23, as, for example, in registry with the connecting portions 33 of said units, for reception of the rail members 20; in the two rail track unit, there would be two of such series of spaced C-shaped open holders 21; for a three rail system, a third series of C-shaped 50 holders would be provided; the device of this invention would be correspondingly conformed to that use thereof.

In Figs. 2, 6, 11 and 12, the invention is shown used for securing a pair of T-shaped rails to a railway bed unit, for which purpose a pair of slide bars 30, 31 (Figs. 6, 7, 8), 60, 61 (Figs. 11, 12, 13, 14) is provided. A single slide bar may be used for moving both rails into the two series of C-shaped open holders from one end of the unit 22, or 23 by the provision of both rail receiving recesses 27 to either the left or the right of the pin 28 or 29, for example, in Fig. 6 (or of pins 28', 29' of Fig. 11).

A description of one slide bar and associated parts will suffice for both throughout the drawings; similar parts will be designated by corresponding reference characters. The means (28, 29, Fig. 2, 28', 29' Fig. 12) 65 serves to locate the units 22, 23 on registering plate 26 and also as a stop means to prevent movement of said units responsive to movement of the bar and prevent excessive movement of the bar. The slide bar 31 (Figs. 6 and 4) has a finger 35 disposed for reciprocating movement in the rail receiving recess 27, so that, when the unit 23 is positioned on the registration plate 26, as shown 70

in Fig. 6, and the slide bar is actuated by any suitable means 34, slide bar finger 35 will be moved into engagement with the end 36 of the miniature rail 20 to move the rail toward unit 23, forcing the rail into the holders 21 of the series carried by unit 23. The means 34 for actuating the slide bar 31 may comprise a piston or plunger 37 reciprocated in the cylinder or actuator 38 which may be an electromagnet, for example, or air pressure cylinder, hydraulic or other means or the like, actuated by suitable valve or other control means operated by the operator, for reciprocating the plunger 37 at the desired times. The reciprocating means 34 may be a rod pivoted, as at 39, on plate 26 at one end, the opposite end having fixed thereto the slide bar 31, and connected, as for example, by a pivot 40 with plunger 37. A bracket 41 may be provided to stabilize the rod 34 in its movement from the (inoperative) full line position in Fig. 1 to the dotted line position there shown at the completion of the cycle of moving the rail into the series of holders 21.

I have found it convenient, in practicing the invention, to manually initially insert the rails 20 into a few of the C-shaped holders 21 immediately adjacent the ends of the unit 23, and then positioning the unit 23 with the pair of rails secured thereto (as shown in Fig. 6) downwardly in the recesses 27. Then a second plate 74 (Fig. 7) may be closed over the unit, as for example, by use of suitable linkage such as shown at 42 (Fig. 9) to the (left hand) dotted line position, holding the unit 23 in position while the rails are inserted into the holders as above explained. Linkage 42 may have an operating bar 75. After the operation has been completed, the plate 74 may be lifted by actuating the linkage 42 to the (right hand) dotted line position shown in Fig. 9, for example. A release lever 43 may be positioned in a recess 44 in registration plate 26 for actuation at an angle to the axis of the bar finger recess 27 and intersecting the same beneath the plane thereof (Fig. 3) so that said lever 43 may be actuated (Fig. 3) to the dotted line position to release the unit 23; in practice, the method is an extremely rapid and accurate one, requiring a minimum amount of attention by the operator.

In the form shown in Figs. 10-14, the device is used for inserting rails into units 22 of relatively straight outline, in which case the slide bars 60, 61 may be movable in keyways 62, 63 in the plate 26. In this form of invention, the device is adapted to accommodate a pair of rail units 22 (Fig. 12) each slide bar 60, 61 engaging one of the pair of rail units to move the same into the series of C-shaped open holders of the units 22. If desired, any suitable means for holding the units 22 in position during operation of the device may be provided. For example, a second closure plate 64 (Fig. 11) may be provided, connected by suitable linkage 65 to the plate 26. The pistons or plungers 37, in the form shown in Figs. 11 and 12, may be straight-line acting pistons, as shown.

The registration plate 26 is provided, in addition to the rail receiving recesses 27, with grooves 45 for the C-shaped holders 21. The opening 76 (Fig. 15) of holders 21 may be formed to approximately the external dimensions of the base portion 46 of the miniature rail 20 so that, after the insertion of the rails therein, said rails will be effectively locked against removal without the use of tools or considerable force. If, as is frequently done, the units 22, 23, are made of plastic materials, said holders 21 may have sufficient "give" so as to initially yield slightly to receive the rails and then return to normal position, effectively locking the rails therein. For that purpose, if desired, the holders 21 may also be proportioned so that their openings 76 are less than the dimensions of the base 46 of the rail

20 to be received therein. Means may be provided on the plate 26, such as the keyway 47 in the Fig. 7 form of plate 26 or the keyways 62, 63 in the Fig. 11 form to receive the units 22, 23. In the Fig. 11 form the rail bed device may be made for one, two or more units, as may also the device of Fig. 1.

Having thus described my invention, what I claim as new and desire to secure by Letters Patent is:

1. An apparatus for assembling a miniature railway track rail onto a miniature railway bed, said bed having a plurality of rail-receiving holders projecting from one face thereof in spaced, aligned relation, said apparatus comprising a first plate having a plurality of recesses complementary to the projecting holders of the railway bed, said bed being positioned on said plate with its projecting holders disposed in said complementary recesses, said first plate further being provided with a rail receiving recess axially aligned with said plurality of recesses, said rail being positioned in said rail receiving recess, a second plate, means to secure the second plate over the railway bed to hold the latter onto the first plate with the projecting holders of the railway bed disposed in said complementary recesses of the first plate, and means extending into the rail receiving recess and movable against the rail to move the rail into the projecting holders of the railway bed.

2. In an apparatus as set forth in claim 1, stop means on said first plate so located as to be disposed adjacent the ends of the railway bed when the latter is so disposed in said complementary recesses of the first plate, to assure registration of the railway bed with the projection holder recesses on the first plate.

3. An apparatus for assembling a miniature track rail onto a miniature railway bed, said bed having two rows of axially aligned, parallel rail receiving holders projecting from one face thereof, said apparatus comprising a plate having two rows of axially aligned parallel projection receiving recesses complementary to the two rows of axially aligned, parallel rail receiving projecting holders, said bed being positioned on said plate with its rows of projecting holders disposed in said two rows of projection receiving recesses, said plate being further provided with a rail-receiving recess aligned with and opening into a row of holder receiving recesses, said rails being positioned in said rail-receiving recesses, means secured to the plate, movable on to the railway bed to secure the railway bed onto the plate with the projecting holders of the railway bed disposed in said complementary recesses of the plate, and means extending into the rail receiving recesses and movable against the rails while the railway bed is so secured onto the plate, to move the rails into the projecting holders of the railway bed.

4. In an apparatus as set forth in claim 3, stop means on the first plate so located as to be disposed adjacent the ends of the railway bed when the latter is so disposed in said complementary recesses of the first plate, to assure registration of the railway bed with the projection holder recesses on the first plate.
